UNITED STATES PATENT OFFICE.

THOMAS F. DURHAM, OF PHILADELPHIA, PENNSYLVANIA.

BLASTING-CARTRIDGE.

SPECIFICATION forming part of Letters Patent No. 748,935, dated January 5, 1904.

Application filed March 4, 1903. Serial No. 146,124. (No model.)

To all whom it may concern:

Be it known that I, THOMAS F. DURHAM, a citizen of the United States, residing at Philadelphia, county of Philadelphia, and State of Pennsylvania, have invented a certain new and useful Improvement in Blasting - Cartridges, of which the following is a specification.

My invention relates to a new and useful improvement in blasting-cartridges, and relates to that class of cartridges in which the explosive is contained within an inner tube, which inner tube is inserted in an outer casting, a fire-extinguishing agent, such as water, surrounding the inner tube upon all sides; and the object of this invention is to construct a cartridge which may be molded and have a tapering or conical end, and the open end of both the outer and inner tube may be sealed by screw-plugs and the fuse or igniting device may pass from the exterior of the outer tube to the interior of the inner tube without going through the side of the outer tube.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a longitudinal sectional view of a cartridge constructed according to my invention; Fig. 2, a plan view of the cartridge; Fig. 3, a cross-section; Fig. 4, a cross-section of the cartridge, showing a modified form of the same.

A represents the outer tube, which is closed at one end, and this closed end is formed tapering or conical, as represented at A'. This conical end is for the purpose of allowing the cartridge to be more easily inserted in the hole drilled in the substance to be blasted. The opposite end of the outer tube or cylinder A is interiorly threaded, as represented at A².

B is the inner tube, which is closed at one end and at the other end is interiorly thread-

ed, as represented at B'. This inner tube is adapted to contain the explosive C and is designed to be held at a distance from the outer tube, and the space between the two tubes is adapted to contain a fire-extinguishing agent, such as water, as represented at D. These tubes may be held separated in any manner; but the means which I have shown in the drawings consists of a series of projections or ribs E, which are formed with the outer tube and extend inward therefrom, as shown in Figs. 1 and 3, and for the purpose of keeping the inner tube from coming in contact with the tapering or conical end A' of the outer tube I provide the lugs or projections E', formed with and extending inward from the outer tube, upon which the inner tube rests. The open interiorly-threaded ends of both the outer tube and the inner tube are adapted to be closed by screw-threaded plugs F and G, respectively. The open end or mouth of the outer tube is not of the same diameter as the body of the tube, but is of sufficient diameter to allow for the insertion of the inner tube. This mouth or open end is formed eccentric to the body of the tube, as illustrated in Fig. 2, and this leaves upon one side of the upper end of the tube a shoulder H, through which is formed an opening I, and the fuse passes downward through this opening and through an opening K, provided through the side of the inner tube. Both the openings I and K are closed around the fuse with soap, glass, or other suitable material to prevent leakage. By this construction it will be seen that it is not necessary to form an opening through the screw-threaded plugs for the fuse, and still the fuse may pass to the inner tube without passing through the side of the outer tube, for if the fuse did pass through the side of the outer tube it might be injured in inserting the cartridge in the drilled hole, and by this construction the fuse may be inserted before the plugs are placed in the tube.

In Fig. 4 I have shown a modification where in the ribs or projections E may be formed conical instead of wedge shape. Both the inner and outer tubes are designed to be molded from a fireproof material, such as a mixture of silica and cement, for the purpose of preventing the cartridge from catching fire

and also to make the tube stronger, so as to cause more resistance, and at the same time to be made at a comparatively small cost.

Of course I do not wish to be limited to the exact construction hereshown, as slight modifications could be made without departing from the spirit of my invention.

Having thus fully described my invention, what I claim as new and useful is—

10. 1. In a safety blasting-cartridge, an outer tube closed at one end, said closed end being formed tapering or conical, an inner tube also closed at one end, the open end of each tube being interiorly threaded, screw-threaded 15 plugs adapted to close said open end, the interiorly-threaded mouth of the outer tube being formed eccentric with the body of the tube, the shoulder thus formed upon one side being provided with an opening extending to 20 the interior of the tube, the inner tube being provided with an opening through its side, a fuse adapted to extend from the exterior of the cartridge through said opening to the interior of the inner tube, and the holes adapted 25 to be closed around the fuse by a plastic waterproof solution, projections extending inward from the outer tube to hold the inner tube at a distance from the outer tube, and projections extending inward from the conical 30 end of the outer tube upon which the inner tube is adapted to rest, as and for the purpose specified.

2. In a safety blasting-cartridge, an outer tube closed at one end, said closed end being 35 formed tapering or conical, an inner tube also

closed at one end, means for holding the inner tube at a distance from the outer tube, the open end of each tube being interiorly threaded, screw-threaded plugs adapted to close said open ends, the interiorly-threaded mouth of the outer tube being formed eccentric with the body of the tube, the shoulder thus formed upon one side being provided with an opening extending to the interior of the tube, the inner tube provided with an opening through its side, a fuse adapted to extend from the exterior of the cartridge through said openings to the interior of the inner tube, and the holes adapted to be closed around the fuse by a plastic waterproof solution, said inner and outer tubes adapted to be molded from a fireproof substance, as and for the purpose specified. 45

3. In a safety blasting-cartridge, an inner and outer tube projections extending inward from the outer tube, said projections adapted to hold the inner tube at a distance from the outer tube, said inner and outer tube and projections being molded from a material composed of a mixture of cement and silica, 50 or like substance, as and for the purpose specified. 55

In testimony whereof I have hereunto affixed my signature in the presence of two subscribing witnesses.

THOMAS F. DURHAM.
